United States Patent Office

Des. 214,021
Patented May 6, 1969

214,021

CAN

Paolo Bacialli, 30 Viale SS. Pietro e Paolo,
Rome, Italy

Filed Nov. 13, 1967, Ser. No. 9,366

Term of patent 14 years

Int. Cl. D9—07

U.S. Cl. D9—44

The figure is a side perspective view of a can embodying my new design;

The side opposite that shown is a mirror image of the side shown and the end not shown is plain and unornamented.

I claim:

The ornamental design for a can, as shown and described.
